ELECTRIC FUSE OF THE CARTRIDGE TYPE

Ernest Moor, Gravesend, England, assignor to
 W. T. Henley's Telegraph Works Company
 Limited, London, England, a British company

Application January 15, 1937, Serial No. 120,743
 In Great Britain January 25, 1936

1 Claim. (Cl. 200—131)

This invention relates to electric fuses and cut-outs of the cartridge type. In fuses of this type the fusible element is disposed in a tubular member and its ends are connected to terminal caps 5 mounted on the ends of the tubular member. In cases where the tubular member or barrel, as it is frequently termed, is of a material such as porcelain that cannot be machined or drilled there arises a difficulty in securing the closure 10 member in a satisfactory manner. Hitherto the closure member or cap has generally been made in the form of a flanged lid which has been secured to the end of the barrel by making a cement joint between the flange and the peripheral surface 15 face of the barrel. This is unsatisfactory in that the cement is liable to disintegrate with the result that the whole fuse may fall to pieces when being handled or after it has been in service for some time.

20 By the present invention we provide a cartridge fuse which is free from the objectionable faults possessed by the type in which the cap is cemented to the barrel.

In the improved construction of cartridge fuse 25 there is fitted on each end of the barrel which houses the fuse element or elements, an apertured metal inner cap and a metal outer cap between which is located the bent over end of the fuse element. The inner cap fits over the end of the 30 barrel and is retained in position by spinning or pressing the edge of its circumferential flange into a circumferential groove in the barrel. The outer cap fits over the inner cap and is retained in position thereon by soldering to the inner cap. 35 With this arrangement the inner cap is secured to the barrel in an inexpensive, reliable and permanent manner and the end of the element can be held in good contact with the inner face of the outer or with the outer face of the inner 40 cap or with both these faces. By making the outer cap a push fit on the inner cap it can readily be detached, for the purpose of inserting new elements into the cartridge, by melting the soldered joint.

45 In order that the invention may be more fully understood an example of a heavy duty cartridge fuse constructed in accordance with the invention will now be described with reference to the accompanying drawing wherein,

50 Figure 1 is a sectional elevation of one half of the fuse, and

Figure 2 is an end elevation of the fuse.

The barrel portion of the fuse shown in the 55 drawing comprises a short cylindrical body 1 of

porcelain having one or more longitudinal channels 2 which extend therethrough and are disposed symmetrically about the axis of the barrel. At each end the external diameter of the barrel is reduced, as shown at 3, and a peripheral groove 4 is provided at the point where the change in external diameter occurs. This groove is roughly of V-shape with the base of the V and the corners at the extremities of the V rounded off, particularly on the side of the groove nearer to the end of the barrel. On the reduced end portion of the barrel is fitted a thin inner cap 5, preferably of copper. This consists of a circular disc suitably apertured to correspond with the channels in the barrel and having a peripheral flange 6 of which the internal diameter corresponds to the external diameter of the reduced portion of the barrel. The depth of the flange is such that its edge 7 extends approximately to the centre of the circumferential groove. The edge 7 is then spun or pressed into the groove 4. The pressure may be applied uniformly around the whole periphery of the flange or at multiplicity of points around the periphery. Preferably a gasket 8 of asbestos or other suitable arc resisting, cushioning material is inserted between the face of the cap 5 and the end of the barrel 1. In each passage 2 is disposed a pair of fuse elements 9. The central parts of these elements 9 are bunched together and located in the centre of the passage but the stems diverge from one another so that near the end of the passage they lie on opposite sides thereof. The extremities of the stems pass through the apertures in the cap and are bent over as shown at 10 and pressed into engagement with the outer face of the cap 5. They may, if desired, be soldered as shown at 11 or welded to the cap or they may be soldered and welded to the cap. The ends of the channels are then closed by plugs 12 of asbestos or the like. Over the inner cap 5 is an outer cap 13 which is of heavier gauge metal, preferably copper or brass, and consists of a circular disc having a circumferential flange 21 of which the internal diameter corresponds to the external diameter of the flange 6 of the inner cap. The outer cap 13 carries contact blades 14, each of which is formed with a base portion 15 which is riveted or welded, as shown at 16, or soldered, as shown at 18, to the outer face of the cap or the base portion may be riveted or welded, as shown at 16, and soldered, as shown at 18, to the outer face of the cap. The outer cap is pressed on the inner cap 5 so as to clamp the ends 10 of the fusible elements between the two 55

caps and is retained in position by soldering the edge of the flange 21 to the flange 6, as shown at 19. Preferably an asbestos gasket 20 is inserted between the bent over ends 10 of the elements and the inner face of the outer cap. It will be appreciated that the operation of spinning or pressing the edge of the inner cap into the groove on the barrel presents no difficulty and does not involve the use of special chucks or other supporting devices because the operation is carried out before the two outer caps carrying the contact blades are fitted.

What I claim as my invention and desire to secure by Letters Patent is:—

- 15 A cartridge fuse comprising at least one fuse

element, a tubular member surrounding said element and having a pair of circumferential grooves in its peripheral surface, and, mounted on each end of said member, an apertured inner metal cap and an outer metal cap, between which is 5 located a bent over end of said fuse element, said inner cap having a circumferential flange and fitting over the end of said member and being retained in position by the engagement of at least part of the edge of its flange in the adjacent 10 circumferential groove in said member and said outer cap fitting on said inner cap and being retained in position thereon by soldering to said inner cap.

ERNEST MOOR. 15
